Primary Examiner — Karen S Acker*Assistant Examiner* — Omeed Agilee(74) *Attorney, Agent, or Firm* — Leason Ellis LLP(57) **CLAIM**

The ornamental design for a tubular catalyst basket, as shown and described.

DESCRIPTION

FIG. 1 is a perspective view of a tubular catalyst basket showing my new design;

FIG. 2 is a right side elevation view of FIG. 1;

FIG. 3 is a left side elevation view of FIG. 1;

FIG. 4 is a top plan view of FIG. 1;

FIG. 5 is a bottom plan view of FIG. 1;

FIG. 6 is a perspective view of FIG. 1 with the mesh removed to show the internal structure; and,

FIG. 7 is a right side view thereof.

The broken lines shown in the figures of screws, rivets, and reinforcements illustrate environmental material that forms no part of the claimed design.
